UNITED STATES PATENT OFFICE.

JOHN S. MAXWELL, OF RICHMOND, INDIANA, ASSIGNOR TO THE STARR PIANO COMPANY, OF RICHMOND, INDIANA, A CORPORATION OF INDIANA.

SAFETY-VALVE.

1,330,329.

Specification of Letters Patent. Patented Feb. 10, 1920.

Application filed October 7, 1918. Serial No. 257,229.

To all whom it may concern:

Be it known that I, JOHN S. MAXWELL, a citizen of the United States, residing at Richmond, in the county of Wayne and 5 State of Indiana, have invented certain new and useful Improvements in Safety-Valves, of which the following is a full, clear, and exact description.

The invention which constitutes the subject matter of this application relates to improvements in safety valves, particularly those which are employed in connection with balloons used for observation purposes. I have found that the ordinary form of these 15 valves have many disadvantages, not only in matters of construction but also in their mode of operation. I have found, for instance, that the thickness of these valves from the innermost to the outermost point 20 is at least 100% greater than necessary, and one of the more important features of this invention is to overcome this defect. In the orthodox type of safety valve employed for this purpose, the greater the amount of the 25 opening of the valve, the greater is the tension on the springs tending to close it. This means that where there is a rather sudden expansion of the gases contained in the balloon, the "patch", to which the valve is connected, is subjected to an undue strain and 30 as a result this patch is liable to be torn rendering the valve functionless and thereby subjecting the balloon itself to the danger of exploding as a result of undue expansion 35 of the gases therein contained. Another of the more important features of my invention therefore consists in overcoming this objection by providing a construction in which a constant or substantially constant 40 tension on the springs is maintained irrespective of the amount the valve is opened. And a still further feature of my invention consists in the provision of mechanism for increasing and decreasing at will the tension 45 on the springs employed to maintain the valve on its seat thereby enabling the valve to be responsive to any predetermined or desired pressure.

Other objects and advantages will appear 50 from the detailed description below taken in connection with the accompanying drawing in which—

Figure 1 is a top plan view of the valve.

Fig. 2 is a section taken on the line 2—2 55 of Fig. 1.

Fig. 3 is an enlarged top plan view of the spring adjusting disk.

Fig. 4 is a transverse section on line 4—4 of Fig. 3.

Fig. 5 is a detail of a valve locking screw. 60

Referring to the drawing in detail, which illustrates one of the preferred embodiments of my invention, the reference numeral 10 designates a base secured in any convenient fashion to the walls of the balloon. Secured to the base 10 is an outwardly projecting annular frame 11 provided with a laterally projecting annular flange 12. The base 10, frame 11 and flange 12 are preferably made of a solid piece of 65 aluminum for lightness and strength, and for the purpose of avoiding the formation or development of any static electricity thereon due, among other things, to the friction of the escaping gases. 75

On the inner side of the lateral flange there is provided an annular valve seat or gasket 13 of flexible or elastic material to enable the valve 14 to seat fluid tight thereon. Secured to any suitable part of 80 the base 10, preferably to the frame 11 or flange 12, is a spider composed of a plurality of arms 15 which converge to a point as indicated at X.

The valve 14 is held normally against 85 its seat 13 by means of the following mechanism: To the lateral flange 12 there are secured double brackets or fulcrum plates 16—17, preferably four in number. To each of these double brackets there is pivotally connected one of the ends of each of the two links 18—19, the other ends of 90 which are pivotally connected to one of the arms of a bell crank lever 20. The intermediate portions of these levers are pivotally connected to brackets or lugs 21 fixed to the outer face of valve 15 and the other ends of which are provided with eyes 22 adapted to be engaged by one of the ends 95 of springs 23, four in number. The other ends of each of these springs are connected to fingers 24 movable laterally in grooves 25 provided in the fixed disk 26 rigidly secured to the valve 14. The fingers are 100 preferably rectangular in contour and the grooves 25 are correspondingly shaped, so that the outer surface of said fingers lie in a plane with the outer surface of the disk.

Superposed upon the disk 26 and fingers 24 is a second disk 27 provided with a plu- 110

rality of spiral slots 28 adapted to receive the studs 29 projecting outwardly from the fingers 24. The disk 27 is normally fixed, as by screws 30, to the disk 26 but it will be seen that if the screws 30 are loosened, a rotary movement may be imparted to the disk 27 around the hub 31 of disk 26. This movement of the disk 27 may be effected by a spanner wrench engaging the holes 32, and when moved in a clock-wise direction it serves through slots 28 and studs 29 to draw the fingers 24 longitudinally toward the axis of rotation of said disk 27 and thereby increase the tension on the springs 23. 15 When this disk 27, however, is moved in a counter-clock-wise direction, the fingers 24 are moved away from the axis of rotation of said disk and the tension of the springs is decreased. It will, of course, be understood that arcuate slots 33 are provided in the disk 27 to receive the fastening screws 30, and the length of these slots is preferably such as to enable a sufficient rotation of the disk 27 to utilize the full effects of 20 the slots 28.

As previously stated the disk 26 is fixed to the valve 14. This may be done in any suitable manner. Passing through the disks 26 and 27 is an eye-bolt 34 to the eye 35 30 of which one end of a cord (not shown) is attached, the other end of said cord being attached to a "patch" (not shown) on substantially the opposite inner surface of the balloon, as will be understood. The fastening nut 36 of the eye-bolt is somewhat elongated to receive the threaded end of the member 37 which passes through the point X of the spider 15, and serves not only to draw the valve into fluid tight relation to its seat, 40 but to lock it in such relation.

From the foregoing it will be seen that as the valve 14 is moved inwardly, the springs and their connections are carried with it. As a result the tension upon the 45 springs is the same or substantially the same whether the valve is fully open or closed or is at any point between these two extremes. It will also be apparent that notwithstanding the improvements which I have made, 50 the valve is simpler in construction, neater in design and cheaper to manufacture than any other heretofore in vogue, and it is to be expressly understood that I do not limit myself to the exact construction illustrated and 55 described, as many changes may be made in points of detail and other embodiments resorted to without deviating from the true spirit and scope of my invention.

What is claimed is:—

60 1. In a safety valve for observation balloons, a base member provided with a valve seat thereon, a valve for said seat, and means for controlling the direction of movement of said valve toward and away from its seat, 65 in combination with resilient means attached

to said controlling means and to said valve for maintaining the latter upon its seat.

2. In a safety valve for observation balloons, a base member provided with a valve seat thereon, a valve for said seat, and means 70 for controlling the direction of movement of said valve toward and away from its seat, in combination with resilient means connected to said controlling means and to said valve for maintaining the latter upon its seat, and 75 means for adjusting the tension of said resilient means.

3. In a safety valve for observation balloons, a base member provided with a valve seat thereon, a valve for said seat, means for 80 controlling the direction of movement of said valve toward and away from its seat comprising bell crank levers pivotally secured to said valve one arm of each of which is pivotally connected to said base, in combination with resilient means connected to the other arm of each of said levers and to said valve for maintaining the latter upon its seat.

4. In a safety valve for observation balloons, a base member provided with a valve seat thereon, a valve for said seat, and means for controlling the direction of movement of said valve toward and away from its seat and for normally maintaining the 90 same upon said seat comprising brackets or fulcrum plates secured to said base member, links one end of each of which is pivotally connected to said brackets, bell-crank levers pivoted to said valve one arm of each 100 of which is pivotally connected to the other end of each of said links, and resilient means connected to the other arm of each of said bell crank levers and to said valve.

5. In a safety valve for observation balloons, a base member provided with a valve seat thereon, a valve for said seat, and means for exerting a substantially uniform pull upon said valve in the direction of its closing movement whether it is fully open, 110 closed or at any intermediate position comprising brackets fixed to said base member, bell crank levers pivoted to said valve, links pivotally connected to said brackets and to one of the arms of each of said bell crank 115 levers, and resilient means connected to the other arm of each of said bell crank levers and to said valve.

6. In a safety valve for observation balloons, a base member provided with a valve seat thereon, a valve for said seat, and means for controlling the direction of movement of said valve and for exerting a substantially uniform pull thereon in the direction of its closing movement whether it is fully 120 open, is closed, or is at any intermediate position, comprising bell crank levers pivoted to the valve one of the arms of each of which is pivotally connected to said base, 125 and resilient means connected to the other 130 arm of each of said bell crank levers.

arm of each of said bell crank levers and to said valve.

7. A construction as specified in claim 6 in combination with means carried by the 5 valve for varying the tension of the resilient means.

8. In a safety valve for observation balloons, a base member provided with a valve seat thereon, a valve for said seat, and 10 means for exerting a substantially uniform pull upon said valve in the direction of its closing movement whether it is fully open, closed or at any intermediate position comprising means for controlling the direction 15 of movement of said valve toward and away from its seat, and resilient means connected to said controlling means and anchored to said valve.

9. In a safety valve for observation balloons, a base member provided with a valve seat thereon, a valve for said seat, mechanism for pivotally connecting said valve to said base, and means for closing said valve and maintaining the same upon its seat 25 comprising a plurality of springs one of the ends of each of which is connected to said mechanism, and a tension adjusting means carried by said valve to which the other ends of said springs are connected.

30 10. A safety valve for observation bal-

loons comprising a base member provided with a valve seat thereon, a valve for said seat, mechanism for pivotally connecting said valve to said base and enabling the valve to open and close, and a plurality of 35 springs one of the ends of each of which is connected to said mechanism and the other ends of which are connected to the valve, in combination with means for varying the normal tension of said springs.

40 11. A spring tension adjusting mechanism for safety valves used in observation balloons comprising two relatively movable disks one of which carries spring connecting fingers movable toward and from the axis 45 of said disks, and the other of which is provided with means for actuating said fingers when it is relatively rotated.

12. A valve device comprising a frame having a transverse valve seat surrounding 50 a fluid passage, a disk-type valve coacting with said seat, a plurality of bell-crank levers fulcrumed on the valve, links connecting said levers with the frame, and spring means wholly supported by said valve and 55 tending to turn the levers in a direction to close the valve.

In testimony whereof I affix my signature.

JOHN S. MAXWELL.
